HIGHWAY-CROSSING SIGNAL

Lemuel F. Howard, Edgewood Borough, Pa., assignor to The Union Switch & Signal Company, Swissvale, Pa., a corporation of Pennsylvania

Application December 11, 1930
Serial No. 502,875

3 Claims. (Cl. 177—329)

My invention relates to highway crossing signals, that is, to signals which are placed at the intersection of a railway and a highway for the purpose of warning users of the highway when 5 a train is approaching the intersection. More particularly, my invention relates to such signals which are adapted to display different aspects according to traffic conditions on the railway.

I will describe one form of highway crossing 10 signal embodying my invention, and will then point out the novel features thereof in claims.

In the accompanying drawings, Fig. 1 is a front elevational view of a highway crossing signal constructed according to my invention. Fig. 2 is 15

an enlarged horizontal sectional view taken on line II—II of Fig. 1. Fig. 3 is a vertical longitudinal sectional view taken on line III—III of Fig. 2. Fig. 4 is a vertical transverse sectional view taken on line IV—IV of Fig. 2. Fig. 5 is 20 an enlarged fragmentary sectional view of the latch mechanism taken on line V—V of Fig. 3. Fig. 6 is a diagrammatic view showing the several circuits controlling the operation of the apparatus illustrated in the preceding views.

Similar reference characters refer to similar parts in each of the several views.

Referring first to Fig. 1, a highway crossing signal embodying my invention is shown as comprising a pole or mast 1 carrying at the top thereof a standard "cross buck" 2. Secured to the mast 1 beneath the "cross buck" 2 is a single light unit 3 of the "flasher" type and beneath this and also secured to the mast 1 is a rectangular housing 4 enclosing the signal apparatus constituting the present invention and which is 30 adapted selectively to display a blank aspect, a "Train coming" aspect or an "Out of order" aspect, according to certain conditions. A sign 5, displaying the words "Train coming signal", 35 may also be secured to the mast 1 beneath the housing 4, if desired.

With reference now to Figs. 2, 3 and 4, the front wall of the housing 4 is formed with an opening 6, protected by a hood 7, and which is 45 closed by a sheet of glass 8. Depending brackets 9 are secured to the top wall of the housing 4 and carry a plurality of electric lamps 10 which are illuminated, when a train is approaching the highway crossing, in a manner hereinafter to be described. Brackets 11 are also secured to the rear wall of the housing and form the support for a reflector 12 which extends longitudinally in the rear of the lamps 10. A section of cylindrical red glass 13 is suitably mounted between the forward ends of the brackets 11 in

spaced relation to the opening 6 and cover glass 8 and gives a distinctive color to the signal indications hereinafter described. A bull's eye lens 14 is provided in one of the end walls of the housing 4, behind which a lamp 15 is mounted by means of a bracket 16 and indicates to traffic on the highway beside the signal whether or not the lamps 10 are illuminated.

A member 17 having the form of a section of a cylinder is mounted for swinging movement, 65 between the glass 8 and the colored glass 13, on rearwardly extending flanges 18 at each end. Secured to the flanges 18 and coincident with the axis of the member 17 are stud shafts 19 which are rotatably mounted in brackets 20 carried by the rear wall of the housing 4. The angle subtended by the member 17 is substantially three times that subtended by the opening 6 and is divided into three portions each displaying a different aspect having predetermined significance to traffic on the highway when moved into registry with the opening 6. In the present instance I have shown the member 17 as having a blank, imperforate lower portion 21 adapted to close the opening 6 to light emanating from the lamps 10, an intermediate portion 22 having the legend "Train coming" stenciled therein, and an upper portion 23 bearing the stenciled legend "Out of order" (Fig. 3). The portions 21 and 22 are preferably painted black but the portion 23 bearing the legend "Out of order" is unpainted and provided with a light reflecting matted surface. This insures that if the lamps 10, from any cause, fail to function, the light of a vehicle approaching the crossing at night will be reflected and cause the legend "Out of order" to appear in black against a light background. Similarly, in the day time, this legend will appear in dark letters due to the contrast between the bright metal and the dark red glass behind the stencil. 90 Also, if a phantom indication exists, the contrast between the bright background and the phantom light reflected by the dark glass back of the stencil will be sufficient to render the legend visible.

Weights 24 are secured to the flanges 18 of the member 17 so as to insure that this member is constantly biased by gravity, toward the position for indicating "Out of order." The member 17 is, however, at times swung in a clockwise direction, as viewed in Fig. 4, against this gravity bias so as to present the blank portion 21 in registry with the opening 6, by means of an electric motor M. This motor is carried by a support or platform 25 which is mounted for vertical pivotal 105 movement.

movement upon a knife edge bearing 26 (Fig. 4). The motor M drives a worm 27 which meshes with and drives a worm wheel 28 which is fixed to a shaft 29. This shaft is journalled in bearings 30 carried by the support 25 and has a roller 31 fixed thereto having a tractive periphery for frictional engagement with a roller 32 fixed to one of the stud shafts 19. The motor M and the parts directly driven thereby are so arranged on the support as to tilt the latter in a counter-clockwise direction under the action of gravity to a position in which it rests upon a stop 33, with the roller 31 out of driving contact with the roller 32. The support 25 is, however, at times swung about its bearing 26 in a clockwise direction against this gravity bias, so as to carry the roller 31 into driving engagement with the roller 32, by means of an electromagnet E. This electromagnet when energized, as will hereinafter be described, attracts an armature 34 which is yieldably secured by spring 35 and an adjustable screw 35¹ to an arm 36 fixed to the support 25. The circuit for the motor M is controlled by a contact device 37-37^a which is mounted upon a block of insulating material 37¹ carried by one of the brackets 11 in a position in which it will be opened by the member 17 when this member is swung to its extreme upper or clockwise position shown by broken lines in Fig. 4.

Normally, that is to say when there is no interruption in the supply of current to the apparatus, the member 17 is permitted to swing in a counter-clockwise direction under the action of gravity when a train approaches the crossing, as will presently be described, and is arrested in its intermediate position so as to display the "Train coming" legend through the opening 6 by means of a latch 38. This latch is pivotally mounted at 39 on one of the brackets 20 and is formed with a depending arm 40, movable into and out of the path of movement of a stop 41 carried by the adjacent flange 18 of the member 17. The latch 38 is also provided with a horizontally extending arm 42 which carries the armature 43 of an electromagnet F (Fig. 3). A leaf spring 44 yieldably tends to maintain the arm 40 in a position without the path of movement of the stop 41 when the electromagnet F is deenergized but when the circuit for this electromagnet is completed, which is the case when a train is approaching the crossing, the latch 38 is swung about its pivot 39 against the action of the spring 44 to a position in which the arm 40 will be engaged by the stop 41 and arrest the movement of the member 17 in its intermediate position shown in Fig. 3.

With reference now to Fig. 6 of the drawings, the apparatus is shown as being controlled by a relay R which is a part of the trackway apparatus and which is energized when the track section adjacent the highway crossing is unoccupied. Under such conditions the electromagnet E is energized by virtue of a circuit passing from a suitable source of electric energy, such as a local battery 45, through wire 46, front contact 47-47^a of relay R, wire 48, winding of electromagnet E, and wires 49 and 50 to battery 45. The energization of electromagnet E attracts its armature 34 and holds the support 25 in its extreme clockwise position against its gravity bias with the roller 31 in frictional contact with the roller 32. This holds the member 17 in its uppermost or normal position with the lower blank portion 21 thereof in registry with the opening 6 in the housing 4 as shown in Fig. 1. The worm and worm wheel driving connection between the motor M and

the member 17 prevents the backward rotation of the parts, when in this position under the weight of the member 17.

I will now assume that a train approaching the highway crossing deenergizes the relay R and causes it to open its front contact 47-47^a and interrupt the circuit just traced through this contact for the electromagnet E. The deenergization of this magnet permits the motor support 25 to drop under the action of gravity and carry the roller 31 out of frictional contact with the roller 32, thus releasing the member 17 and permitting it also to swing downwardly under gravitational influence.

The deenergization of the relay R also causes it to close its back contact 47-47^b and cause the energization of the electromagnet F by virtue of a circuit passing from battery 45, through wire 46, back contact 47-47^b of relay R, wire 51, winding of electromagnet F, and wire 50 to battery 45. The energization of the electromagnet F swings the latch 38 to a position in which its arm 40 will be engaged by the stop 41 carried by the flange 18 and will thus arrest the downward movement of the member 17 in its intermediate position in which the legend "Train coming" is in registry with the opening 6 as shown in Figs. 3 and 4. The closing of back contact 47-47^b of relay R also causes the illumination of the lamps 10 by virtue of a parallel circuit passing from battery 45, through wire 46, back contact 47-47^b of relay R, wire 52, lamps 10, and wires 53, 49 and 50 back to battery 45, thus rendering the legend interposed between the lamps 10 and the opening 6, visible to traffic on the highway.

As the member 17 gravitates downwardly, as above described, it permits the contact 37-37^a in the circuit for the motor M to close but this does not complete the motor circuit at this time for the reason that this circuit is now open at front contact 47-47^a of relay R.

As soon as the train passes the highway crossing, the relay R again becomes energized and opens its back contact 47-47^b in the circuits just traced through this contact for the electromagnet F and the lamps 10. The reenergization of relay R also closes its front contact 47-47^a which re-establishes the circuit previously traced through this contact for the electromagnet E. The energization of this magnet again causes it to attract its armature 34 and to swing the support 25 about its pivot 26 in a clockwise direction against its gravitational bias to a position in which the roller 31 again frictionally engages the roller 32. A parallel circuit is also established under these conditions for motor M passing from battery 45, through wire 46, front contact 47-47^a of relay R, wire 54, winding of motor M, wire 55, contact 37-37^a, which is now closed, and wires 53, 49 and 50 to battery 45. The energization of motor M causes the rotation of the roller 31 through the medium of the worm 27 and worm wheel 28 which in turn causes the rotation of roller 32, in a clockwise direction. The rotation of roller 32 swings member 17 upwardly to a position in which the lower blank portion 21 thereof registers with the opening 6 in the housing 4. As the member 17 reaches the limit of its upward movement, it opens the contact device 37-37^a and interrupts the circuit just traced through this contact for the motor M.

The circuit for the electromagnet E, however, remains intact and, therefore, this magnet holds the roller 31 in engagement with the roller 32, thus maintaining the member 17

in its uppermost position until again released, as hereinbefore described.

My invention also contemplates the provision of means for indicating to traffic on the highway when the apparatus is not functioning through a failure of the source of power. For example, I will assume that the battery 45 becomes disconnected, so that the electromagnet E releases its armature 34 and so permits roller 31 to drop out of engagement with roller 32. This releases member 17 and permits it to swing downwardly in the manner previously described. In this event however, the electromagnet F is not energized and, consequently, the latch 38 is not operated to arrest the descent of the member 17 in its intermediate position. As a result, member 17 swings downward to the extreme limit of its movement, in which position it is arrested by a stop 56 with the upper portion 23 bearing the legend "Out of order" registering with and visible through the opening 6. When the power failure is remedied, electric current is supplied to the motor M and the member 17 is swung to one of its upper positions in the manner hereinbefore set forth.

Although I have herein shown and described only one form of highway crossing signal embodying my invention, it is understood that various changes and modifications may be made therein within the scope of the appended claims without departing from the spirit and scope of my invention.

Having thus described my invention, what I claim is:

1. A highway crossing signal comprising a housing having an opening therein, a lamp disposed within said housing, a member mounted in said housing for movement in opposite directions between said opening and said lamp and biased in one direction and having portions pervious to light emanating from said lamp and bearing different indicia and a portion imperious to such light and forming a closure for said opening, a support mounted for movement between a first and a second position and biased to said first position, an electric motor on said support for moving said movable member in opposition to its bias, means effective when said support is moved to said second position for operatively connecting said motor with said movable member, and an electromagnet for moving said support from its first to its second position.

2. A highway crossing signal comprising a housing having an opening therein, a lamp disposed within said housing, a member mounted in said housing for movement in opposite directions between said opening and said lamp and biased in one direction and having portions pervious to light emanating from said lamp and bearing different indicia and a portion imperious to such light and forming a closure for said opening, a support mounted for movement between a first and a second position and biased to said first position, an electric motor on said support for moving said movable member in opposition to its bias, means effective when said support is moved to said second position for operatively connecting said motor with said movable member, an electromagnet for moving said support from its first to its second position, and latch mechanism for controlling the extent of movement of said movable member by its bias.

3. A highway crossing signal comprising a housing having an opening therein, a lamp disposed in said housing, a shaft, a member operatively connected with said shaft for movement in opposite directions between said opening and said lamp and constantly biased in one direction, said member having different indicia adapted to be selectively disposed in registry with said opening, a first pulley on said shaft, a support mounted for movement between two positions and constantly biased in one direction, an electric motor mounted on said support, a worm wheel mounted on said support and driven by said motor, a second pulley driven by said worm wheel, a first electromagnet for moving said support against the action of its bias to a position in which said second pulley frictionally engages said first pulley, a latch for arresting the movement of said member in an intermediate position, a second electromagnet for operating said latch, a relay, a normally closed contact controlled by said member and arranged to become opened when and only when said member is moved to an extreme position in opposition to its bias, a source of electromotive force; a circuit for said motor including said source, said normally closed contact, and a front contact of said relay; a circuit for said first electromagnet including said source and a front contact of said relay, and a circuit for said second electromagnet including said source and a back contact of said relay.

LEMU F. HOWARD.
